DESIGN FOR A GAS STORAGE UNIT

Phillip M. Ahlstrand, Kenmore, and George W. Patch, Jr., White Plains, N. Y.

Application August 2, 1946, Serial No. 132,220

Term of patent 14 years

(Cl. D58—17)

To all whom it may concern:

Be it known that we, Phillip M. Ahlstrand and George W. Patch, Jr., residing at Kenmore, in the county of Erie, State of New York, and White Plains, in the county of Westchester, State of New York, respectively, have invented a new, original, and ornamental Design for a Gas Storage Unit, of which the following is a specification, reference being had to the accompanying drawing, forming a part thereof.

In the drawing,

Fig. 1 is a side elevational view of a gas storage unit, illustrating our new design;

Fig. 2 is a plan view of the gas storage unit illustrated in Fig. 1; and

Fig. 3 is an end elevational view of the gas storage unit illustrated in Fig. 1.

We claim:

The ornamental design for a gas storage unit, substantially as shown.

PHILLIP M. AHLSTRAND.
GEORGE W. PATCH, JR.
